UNITED STATES PATENT OFFICE.

JOHN V. CIZEK, OF CLUTIER, IOWA.

ADJUSTABLE BOLSTER STANDARD FOR WAGONS.

Application filed March 29, 1926. Serial No. 98,228.

My invention relates to adjustable wagon bolster standards, and the object of my improvement is to supply standards of this class in adjustably spaced and coupled pairs, 5 permitting them to be firmly secured adjustably upon opposite sides of a bolster with widened bearing upon a sideboard, and including supporting elements for auxiliary standards removably associated therewith.

10 The invention herein therefore resides in the combination and arrangement of parts and in the details of construction herein-after described and claimed, it being understood that changes in the precise embodiment of invention herein disclosed can be made within the scope of what is claimed 15 without departing from the spirit of the invention.

In the annexed drawings, Fig. 1 is an end 20 elevation of my paired standard parts as adjustably secured together and to a bolster end, parts of the side and bottom boards being broken away. Fig. 2 is a side elevation of the same, with the wagon side and 25 bottom boards shown in cross section. Fig. 3 is an elevation of the inner side face of one of the standards as taken alone. Fig. 4 is a top plan of one of said standards alone, but having an auxiliary stake mounting element removably secured thereon. Fig. 5 is a bottom plan view of one of said auxiliary elements.

The numerals 16, 17 and 18 respectively denote a bolster for, and the bottom and 30 side boards for a wagon. The outer end of said bolster projects beyond the side board 18. The numeral 1 denotes a pair of like standards, each having at the bottom an angularly directed projection 3 which 35 abuts upon one side face of said bolster, so that the pair of projections of the pair of standards are in contact with opposite vertical faces of the bolster and are secured 40 detachably thereto by the same through bolts 5 and nuts 6. The projecting parts 45 3 are preferably directed from the standards 1 at other than a right angle, so that the bolts may traverse the bolster out of longitudinal alinement with each other to 50 avoid splitting the bolster.

The edge of each standard 1 which contacts with the outer surface of the sideboard 18 is broadened at 2 to afford a widened bearing support thereagainst. The standards 1 of each pair have like apertured and

superposed lugs 7 and 9 on their opposed faces, of which the lugs 7 on the two standards are out of horizontal alinement so that they may closely overlap each other, and both have longitudinal slots which may open 60 into each other vertically in whole or in part according to their relative longitudinal adjustments.

When so relatively adjusted, these paired overlapping lugs 7 may be secured together 65 by means of bolts 14 and nuts 15. By this means the standards 1 may be adjustably mounted upon bolsters of different widths. In case it is desired to have means for extending the side supports upwardly along 70 additional superposed sideboards 18, or to retain certain kinds of loads upon the wagon box when the loads reach above the first sideboard, I employ the following auxiliary devices. Each device consists of a ring 10 75 having a shoulder 11 and thereabove a projection 12 of less thickness apertured at 13. The projection may be placed upon the topmost one of each pair of lugs 7 with its aperture 13 in line with the apertures of 80 these lugs beneath, and the whole fastened together by means of the same bolt 14 and nut 15 as shown in said Fig. 1. Then a stake as indicated by the dotted lines in 85 said figure may be seated in the apertures of the rings 10 to project upwardly above the sideboard 18 as far as desired. The lugs 9 near the bases of the standards project in horizontal alinement toward each other 90 and their apertures may receive screws 95 passed into the bolster below. The lower end of the stake in the rings 10 may then stand upon these lugs 9 when nearest together, and when farther apart, upon the top of the bolster. The shoulders 11 of the 95 rings 10 fit against the outer edges of the paired lugs 7, preventing rocking of the rings. The standards may be used without the rings. It will be seen that the pair of standards afford wide bearings upon the 100 sideboard, and are firmly secured adjustably to opposite faces of the bolster supporting each other against vertical displacements.

Having described my invention, what I 105 claim as new, and desire to secure by Letters Patent, is:

1. In combination, a wagon bolster, a pair of spaced standards having overlapping lugs 110 adjustably fastened together to vary their

spacings, and means for fastening said standards upon the bolster when so relatively adjusted apart.

2. In combination, a wagon bolster, a pair of spaced standards having superposed pairs of longitudinally slotted overlapping lugs, means for securing said lugs together in longitudinally adjusted positions, said means traversing the superposed slots, and means for adjustably securing said standards upon opposite sides of the bolster.

3. In combination, a wagon bolster, a pair of spaced standards having basal projections directed thereto at other than a right angle to be opposed to opposite faces of the bolster, means for securing said projec-

tions to the bolster detachably, said standards having lugs on their inner faces connected together separably for relative longitudinal adjustments, said standards having alined lugs below the said pairs of lugs, and means for fastening said alined lugs upon the top of the bolster.

4. In combination, a wagon bolster, a pair of spaced standards secured upon the bolster detachably, said standards having overlapping lugs, and rings mounted detachably in vertical alinement upon the lugs in spaced relation to receive a stake therein resting basally upon the top of the bolster.

In testimony whereof I affix my signature.

JOHN V. CIZEK.
